CLOTHESLINE PROP

Anthony Kovalik, Whitaker, Pa.

Application March 20, 1935, Serial No. 12,071

2 Claims. (Cl. 248—353)

This invention appertains to new and useful improvements in clothes line props and more particularly to a prop of the extensible type.

The principal object of the present invention is to provide a prop which can be easily operated to an extended or retracted position.

Another important object of the invention is to provide a prop wherein the parts are constructed in such a sturdy manner as to substantially preclude the probability of defects occurring, unless by accident.

Other important objects and advantages of the invention will become apparent to the reader of the following specification.

15 In the drawings:

Figure 1 represents a side elevational view of the prop.

Figure 2 represents a rear elevational view of the prop, fragmentarily showing the upper portion thereof.

Figure 3 represents a fragmentary vertical sectional view taken substantially on line 3—3 of Figure 5.

Figure 4 represents a cross sectional view taken substantially on line 4—4 of Figure 1.

Figure 5 represents a front elevational view of the prop.

Figure 6 represents a fragmentary detailed sectional view taken substantially on line 6—6 of Figure 1.

Figure 7 represents a fragmentary detailed sectional view taken substantially on line 7—7 of Figure 1.

Referring to the drawings wherein like numerals designate like parts, it can be seen that numerals 5—5 represent vertical parallel members of the lower section which is telescoped by the upper section generally referred to by numeral 6.

40 The opposed sides of the parallel members 5—5 are each provided with a pair of parallel grooves 7—7 and to receive the cleats 8—8 of the corresponding side of the slide post 9 of the telescopic section 6.

45 The lower ends of the vertical members 5—5 engage into the socket structure 10 where they are secured by suitable means 11 and from this socket structure 10 depends the ground engaging spur 12.

50 Cross plates 13—14 bridge the upper portion of the members 5—5, the plate 13 being provided with a rockable lever 15 thereon provided with

a pin 16 at one end for disposition through the opening 17 in the plate 13 while the handle portion 18 on this lever has an opening therein for receiving the outstanding pin 19 on the plate 13. A coiled compressible spring 20 is convoluted on the pin 19 and interposed between the plate 13 and the handle portion 18 of the lever 15 to maintain the pin 16 engaged through the opening 17 and into one of the openings 21 of the post 9, which openings 21 register with openings 10 in the elongated metal strap 22 which strap is secured by screws or other suitable means 23 to one side of the post 9 in the manner substantially shown in Figures 3 and 5, a portion of this strap being buckled outwardly as at 24 (see Figures 1 15 and 5) to provide a handle whereby the post can be conveniently lifted.

A square collar or ferrule 25 is disposed around the upper portion of the post 9 and secured in place by the element 26, this ferrule 25 also serves 20 to secure the upstanding inturned hook members 27—27 in the position substantially shown in Figure 6, the hooks 27 of course engaging the line with which the prop is to be employed.

Obviously the prop can be adjusted to any 25 length desired and retained in this position until further adjustment is required.

While the foregoing specification sets forth the invention in specific terms, it is to be understood that numerous changes in shape, size, and materials may be resorted to without departing from the spirit or scope of the invention as claimed hereinafter.

Having thus described my invention, what I 35 claim as new is:

1. A clothes line prop comprising a lower section, an upper section adapted to telescope the lower section, said upper section being provided with an elongated reinforcing strap secured to the same and provided with an outwardly buckled portion defining a handle.

2. A clothes line prop comprising a lower section of hollow construction and provided with an elongated slot therein, an upper section adapted to telescope the lower section, said upper section being provided with an elongated reinforcing strap secured to the same and provided with an outwardly buckled portion defining a handle projecting upwardly through the said slot of the lower section.

ANTHONY KOVALIK.
